Inventor:

Walter Huber

9 Germantown
- Alton, Ill.

UNITED STATES PATENT OFFICE.

WALTER HUBER, OF PFORZHEIM, GERMANY.

WATCHCASE.

Application filed March 11, 1926, Serial No. 93,927, and in Germany September 30, 1925.

This invention relates to a case adapted for any clockwork or watchwork mechanism and having a hinged case member which may be opened and swung backward to serve to support the watch in a substantially vertical or slightly inclined position, so that the watch, an alarm or a travelling clock, may be used as a clock to be placed on the toilet table or on the writing table.

10 Supports for or on watches are known, but they present the inconvenience that they are either of complicated construction, the price of the watch being consequently increased, or that the watch does not stand securely.

The inconveniences are avoided by the invention.

The novelty consists in that, for transforming a watch into a clock, a case member on the front side of the watch is hingedly mounted so that it can be turned backward and forms in this position a good support for the watch.

An embodiment of the invention is shown, 25 by way of example, in the accompanying drawing, in which:—

Fig. 1 shows a case watch, constructed according to the invention in side elevation.

Fig. 2 is a front elevation of the case 30 watch shown in Fig. 1.

Fig. 3 shows in side elevation the watch standing upon a table.

Fig. 4 is a front elevation of Fig. 3.

The cover member 3, hingedly fixed by 35 means of a hinge 2 on the lower edge of the watch case 1 of rectangular shape, is normally held in the closed position by means of a spring hook 4.

By a pressure exerted for instance upon 40 the crown 5 on the stem of the watch the spring hook 4 is released so that the cover member 3 is turned back from the position, indicated in dash and dot lines in Fig. 3, into the supporting position by the action 45 of a strong spring which might, for instance, be located in the hinge 2, the case

member 3 oscillating through an angle slightly more than 270°.

In this position the member 3 forms a very stable base support for the watch case 50 1 which has a bevelled edge 6 bearing on a bevelled edge 7 of the cover member 3, such bevelled edges forming direct abutments between the watch case and cover to sustain the weight of the open case and to 55 relieve the hinge from such weight.

The not ornamented or unfinished, cup-shaped inner face of the cover member 3 is turned when in this position towards the table plate 8 (Fig. 3) and not visible, whilst 60 the generally ornamented and decorated outer surface of the case member 3 is visible. An attractive watch structure may thus be furnished without the expense of finely finishing the inner face of the cover 65 member, an item of importance in the manufacture of watches which must be of good appearance but at the same time cheap.

It is almost impossible that the watch supported in this manner, be upset. The dial 70 9 is in an inclined position so that it is easy to be seen.

The watch case might be of hexagonal or circular shape and of any dimension and material and watches of any type may 75 be fitted with the hinged case member 3.

I claim:—

A time piece comprising an open-faced case, a cover for the open face of the case, said case and cover having beveled marginal 80 abutment surfaces, and a hinge uniting the case and cover at the intersection of said abutment surfaces so as to adapt the cover to be swung backward to a horizontal position and at an angle to the case to support 85 said case in an upright position, in which positions of the case and cover the said abutment surfaces are brought into contact to assist the hinge in supporting the weight 90 of the case and its contents.

In testimony whereof I affix my signature.

WALTER HUBER,
